AMMUNITION FEED AND CONTROL
SYSTEMEdward J. Meyer, Normandy, Mo., assignor to
Curtiss-Wright Corporation, a corporation of
Delaware

Application March 5, 1945, Serial No. 581,131

16 Claims. (Cl. 89—33)

1

The present invention relates to ordnance installations in general and is more particularly concerned with improvements in the operation of ammunition booster systems so that the feeding of ammunition to an automatic gun may be accurately synchronized with the gun operating cycle.

Heretofore, the attainment of free and uninterrupted gun firing operations has been exceedingly difficult in the cases where a booster device exists in the ammunition feed system. There are a number of reasons why these ammunition booster systems have failed to overcome the objectionable characteristics prevailing, a principal objection being that the booster device has been permitted to function in the system as an independent and uncontrolled agency thereby allowing the device to overfeed ammunition or to continue the feed when the gun has stopped firing. It has been found that the belt loads on the booster device are not sufficient to bring the device to a rapid stop since the inertia effects of the belt moving at high speed produce a detrimental over-run or coast. Consequently the rounds of ammunition actually pile up in the chute between the booster and gun and produce a jam impossible for the gun to break.

According to the present invention the system of boosting an ammunition belt toward the gun has been greatly improved, so much so that ammunition can not be caused to pile up or jam in the chute and thus produce or contribute to faulty gun operation. The improved booster system may be adapted for any arrangement of gun and remotely positioned ammunition case or magazine. In general, the present invention provides a simple and positive control for the ammunition booster device so that the action of the booster device is made to synchronize with and become a function of the gun operation thereby preventing the occurrence of chute jams, overfeed to the gun and objectionable ammunition belt drag loads on the gun feeding mechanism.

The invention has as its principal object the provision of a synchronized ammunition booster system for automatic guns so that operational failure of the guns will be minimized or substantially eliminated.

It is an object to provide an ammunition booster control system which shall be rendered initially operative through the gun trigger system and which shall thereafter function to supply ammunition to the gun at a rate just sufficient to assure normal gun action.

Still a further object of this invention is to provide an ammunition booster system particular-

2

ly suitable for use in aircraft, and to utilize the booster for moving belted ammunition to an automatic gun from a remotely located magazine, thereby reducing the ammunition drag load on the gun, and especially the drag load developed during accelerated maneuvers of the aircraft.

An object of the invention is to provide a control device for altering the operation of the synchronized booster system during the periods when gravitational accelerations developed by the gun carrier's space movements produce forces sufficient to impede the free functioning of the synchronized system whereby the impedance may be overcome by the control device to permit continuous and free operation of the booster system.

Another object is to provide a control device of the noted character which is directly and adjustably responsive to centrifugal and gravitational forces for its operation and to relate the device with an electric power booster motor control switch in a manner causing the switch to have a control phase for synchronizing other parts of the system or to cut off said switch thereby eliminating synchronized action in the system.

25 A further object resides in the form and construction of the controlling device to facilitate its assembly and to give assurance of reliable operation, there being included provisions for making adjustments to provide a selective range of operation.

These and other objects will be set forth in greater detail in the following description relating to the accompanying drawings, in which:

Figure 1 is a fragmentary view, in perspective, of the ammunition booster unit and controlling system, certain portions of the structure being broken away for clarity.

Figure 2 is an end elevation of a typical automatic gun wherein certain details of the recoil type ammunition feed mechanism of the gun have been shown in a schematic manner as will appear presently.

Figures 3 and 4 illustrate, schematically, successive positional phases of operation of the control mechanism associated with the ammunition booster unit.

Figure 5 is an electrical wiring circuit which may be incorporated in the control system for the ammunition booster unit.

Figure 6 is a side elevational view of a modified control device shown in operative position (full line) and in non-operative position (dotted line), certain portions being cut away to show details.

Figure 7 is a partial detailed plan view from the under side of the control device of Figure 6.

Figure 8 is a detailed sectional elevation at line 8—8 of Figure 6 and

Figure 9 is a general view in perspective of an automatic gun and turret installation in an aircraft indicated in outline only, the particular features, details of construction and assembly of the present invention being clearly emphasized in other views.

Specifically, the booster organization (Figure 1) includes a rotary drum 10 having a pair of axially spaced sprocket members 11 mounted thereon for rotation with the drum. A typical sprocket is shown clearly in Figures 3, 4 and 6. An electric motor 12 (Figure 5) and driving connections (not shown) are housed internally of the drum 10 while the drum and sprocket unit is rotatably carried in a housing structure 13 as shown. The sprocket members 11 (only one being shown) are formed with tooth elements 14 (Figures 3 and 4) suitably spaced to receive successive shell cases 15 of the ammunition belt. The belt is made up of the shells 15 linked together by the usual and well-known separate looped elements 16 which encircle the shell cases. This belt arrangement conforms to conventional practices and further description is believed unnecessary.

The belted rounds of ammunition are placed initially in a container or magazine 28 such that the belt may be led out of the magazine at the zone 21 and into the path of travel of the booster sprockets 11 where it is positioned in engagement with the sprocket teeth elements 14. The ammunition belt is then directed through a sheet metal or other rigid type chute structure 22 extending along the top surface of the magazine and in the direction of the gun 23. The rigid chute structure 22 may extend the full distance to the gun 23 or it may be terminated at any desired point whereupon a flexible type chute structure (not shown) can be used to direct and confine the belt over the remaining distance to the gun. One practice is to employ a rigid chute which extends to within approximately twenty to twenty-five rounds of ammunition from the gun and to insert a flexible chute means over the remaining span. This allows considerable unrestrained movement of the gun for purposes of aiming at a rapidly moving target, such as a hostile airplane. Moreover, the rigid chute portion reduces the build-up of drag loads on the gun and produces definite improvement in the ability of the gun feed mechanism to draw in the belted shells positioned in the chute.

The feed mechanism (Figure 2) associated with and forming a part of the gun 23 is positioned in the feed chamber 24 and comprises a feed pawl 25 pivotally mounted on a reciprocating cross-head or slide block 26 which is, in turn, moved by an oscillating member 27 forming a part of the gun recoil unit (not shown). The feed pawl 25 is spring urged into positive engagement with the shell cases as shown so that as the driving member 27 moves slide block 26 to the right, as viewed in Figure 2, the ammunition belt is drawn into the chamber 24 and the empty belt link 16 ejected at the opposite side from the ammunition feed side. The stroke of the slide block 26 is just sufficient to advance each round of ammunition to the midpoint of the chamber where it may be withdrawn from the link and moved into the gun breech. The return movement of pawl 25 momentarily releases the ammunition belt and therefore a stop pawl 28 is provided to prevent the belt from back-

ing out of the feed chamber. The gun feed mechanism just described conforms to conventional practice and under normal conditions is sufficiently powerful to draw the ammunition belt into the gun directly from the magazine. A normal condition presupposes that the magazine will be placed near the gun and on approximately the same level so that the weight of the belt and shell cases will not impose too great a load or drag on the feed mechanism of the gun.

However, there are many gun installations and arrangements where it is impossible or impractical to place the ammunition magazine in a position suitable for minimizing the belt loads on the gun. A typical arrangement in this latter category is the turret gun (Figure 9) wherein the gun is flexibly mounted at the upper portion of the turret structure and the magazine is positioned near the floor of the turret and considerably below the level of the gun feed chamber. In this latter case it is the practice to provide a booster device, usually of electrical type, at some point in the line of travel of the ammunition belt. The purpose of the booster device is to reduce the ammunition belt load on the gun by applying an extra push or boost so that the net load imposed upon and experienced by the gun feed mechanism is maintained within permissible limits. If the ammunition belt drag load is adjusted properly, the flow or movement of shells toward the gun can be facilitated and positive gun operation assured.

One form and arrangement of the synchronized booster control system is illustrated in the drawing as an electrically operated booster unit related with the electric circuit (Figure 5), this circuit being controlled by a switch element movable with the gun trigger indicated diagrammatically at 29. The power line 30 for the motor 12, the latter being housed in booster drum 10, is led to a terminal block 31 (Figure 1) which is secured to a sheet metal bracket 32 carried on the booster supporting structure 13. The terminal block is provided with a series of cable connector posts, posts 33 and 34 being selected for the power input line 30. From terminal block posts 34, 35 and 36 three lines 37, 38 and 39 connect with the motor 12 and are arranged to provide current for operating the motor forwardly or reversely. The direction of motor rotation is directly controlled by a single pole, double throw snap switch 40 mounted on the structure 13 and having circuit connections 41, 42 and 43 with the respective terminal block posts 33, 35 and 44. A resistance unit or coil 45 housed in member 46 and carried on supporting elements 47 secured to the bracket 32 is suitably connected to terminal posts 36 and 44 by short leads 48 and 49 so as to be positioned in the motor circuit and on the reversing side thereof. The motor 12 (Figure 5) is provided with a field coil 50 for forward rotation (clockwise when viewed from Figure 1) and a reversely wound field coil 51 for reverse rotation (counter-clockwise when viewed from Figure 1). Full line current is applied to the field coil 50 through lines 37 and 38, while the field coil 51 is connected in series with the resistance unit 45 so that a reduced line current is available for reverse rotation.

The means for controlling the operation of the motor 12 and its direction of rotation in accordance with the firing cycle of the automatic gun 23 is the snap switch 40. This switch comprises (Figures 3, 4 and 5) a central contact arm 55 which is forced to assume either of two positions

by means of a resilient operating arm 56 and a co-acting toggle spring 57. The spring 57 is carried between the switch arm 55 and operating arm 56 and is capable of assuming the positions shown in Figures 3 and 4 whereby the arm 55 is forced to move with considerable snap in a direction opposite to the movement of arm 56. To either side of the contact arm 55 are fixedly positioned cooperating arms 58 and 59 whereby upon movement of the contact arm 55 a complete electrical circuit is made through the motor field coils 50 and 51, respectively. The arm 55 is provided with a silver or other suitable double faced contact point 60, as shown, while the arms 58 and 59 are provided with similar contact points 61 and 62 respectively. The several switch arms 55, 58 and 59 are mounted between a series of insulating blocks 63 and secured in assembly by suitable bolts 64, all as clearly shown.

Referring again to Figures 1, 3 and 4, it will be observed that snap switch 40 is mounted, by means of a suitable bracket 53, on the booster motor supporting and housing structure 13 at the end wall thereof and in a position overlying the line of travel of the belted cartridge cases 15. More specifically the switch is positioned near the base portion of the shells where the spring leaf type operating arm 56 can be arranged in its most advantageous position closely adjacent the shell cases. The outer end of arm 56 is provided with a roller element 65 and roller mounting fork 66, the arrangement being such that the roller 65 projects into the path of travel of each shell case. As a consequence, operating arm 56 is made to move away from and toward the shells as each thereof moves under and away from the roller 65. The arm 56 is given an initial set or is placed in an initial position which urges the roller 65 into the path of the ammunition belt shells thereby assuring that the roller will always be in rolling contact with the shell cases and will move into the spaces or depressions between the shell cases. For the purpose of further discussion the term "crest" will be understood to refer to the position of roller 65 when riding upon the shell case at the point of maximum rise or lift of the roller and associated arm. The terms "depression" or "valley" shall be taken to refer to the position of the roller 65 when it rides down between adjacent shell cases with the resulting greatest possible fall. For example a "crest" position is shown in Figures 1 and 4, while the "depression" is shown in Figure 3.

In operation, the switch or trigger member 29 (Figure 5) is closed only when it is desired to fire the gun. The resulting recoil action of the gun will initiate a forward, step-by-step or jerky movement of the ammunition belt. This intermittent belt advance is necessarily established by the reciprocating gun feed mechanism and it will always be present in the system. In prior boosted ammunition feed systems, the booster unit or device is a continuously operating agency which has no coordinated relation with the action of the gun. However, with the present system of assisted ammunition feed the booster device is made to synchronize its operation with the gun action. This synchronized feed is accomplished by timing the action of the snap switch 40 with the intermittent action of the gun and also by placing this switch in direct control of the booster driving motor. The result is that switch 40 will cause booster motor to operate forwardly and reversely in alternating cycles which are exactly or substantially equal to the gun operating cycles.

Referring to Figures 1 and 4, it will be observed that one possible initial position of the operating arm 56 of switch 40 is on the crest of a shell case 15. If at this time the gun is fired, closure of trigger switch 29 (Figure 5) will energize the booster motor as follows: Current will flow from line 30 through terminal 34, line 37, motor field coil 50, return line 38, terminal 35, line 42, switch contacts 61 and 60, line 41 to terminal 33 and then back into the power line 30 through trigger switch 29. Motor 12 will immediately rotate clockwise (as viewed in Figure 1) and feed the ammunition toward the gun 23. The rotation of motor 12 will cause sprocket 11 to move the shell out of a crest position and thereby permit the roller 65 and arm 56 to approach the position of depression which is between two adjacent shells (Figure 3). At some preselected point in the fall of the roller 65, switch arm 55 will be snapped over to a position where contacts 60 and 62 are closed. In this position, the motor reversing field coil 51 is energized as follows: Current flows from line 30 through terminal 34, line 37, field coil 51, return line 39, terminal 36, line 48, resistor coil 45, line 49, terminal 44, switch line 43, contacts 62 and 60, switch line 41, terminal 33 and back to the power line 30 through trigger switch 29. The tendency of the motor will be to rotate counter-clockwise (as viewed in Figure 1) thereby exerting an influence to return the roller 65 to its crest position on the same shell case, as before. If the time intervals for power reversal are equal to power forward time intervals the motor will simply oscillate between the same crest and depression positions and no forward movement of the ammunition can take place.

Forward movement or progressive feeding of the ammunition belt is accomplished by properly timing and correlating the position of the snap switch roller 65 and the current strength in each of the motor field coils 50 and 51. The booster motor is generally rated at a speed of approximately 10,000 to 12,000 R. P. M. on 24 volts direct current, but is equipped with a suitable gear reduction (not shown) so that the belt engaging sprockets rotate at the considerably reduced speed of approximately 90 to 110 R. P. M. It is obvious that when full line voltage is thrown on the motor the sprockets will come up to speed almost instantly and for purposes of this discussion it will be so considered. Therefore, the electrical system for the booster motor is arranged to supply full line current when the snap switch 40 is in the forward running position (Figure 4) which corresponds to a full rise or crest position. Also full line current is maintained over a substantial deviation to either side of this crest. On the other hand the power reverse cycle for the motor 12 has been modified to an extent sufficient only momentarily to reverse the current supply under normal operating conditions and with the roller 65 in a closely defined depressed zone. Furthermore, the tendency for the motor to reverse its rotation has been considerably damped by the insertion of resistor 45 in series with the reversing field coil 51. This resistor acts to reduce the line voltage thrown on the motor and hence cuts down the rapidity of motor reverse speed pick up. This latter action is generally referred to as "plugging" which means that by reversing the current the motor is effectively electrically braked for quick stoppage.

In this way an oscillating motion is imparted to the ammunition belt which motion can be made to coincide with the gun feed motion for

assuring a positive and regulated flow of cartridges into the gun. The fact that full line current is made available for the belt feed cycle and reduced line current for the belt reverse cycle makes it entirely possible to carry the belt of ammunition over the periods of depression of the switch roller 65 and into the following crest periods or roller rise. This carry-over result obtains due to the powerful thrust of the motor in the feed direction and the relatively weak thrust developed in the reversing direction. Combined with this electrical circuit arrangement is the control switch 40 which is positioned with respect to the cartridge cases or shells 15 for maintaining the roller element 65 in its power on phase position during a time interval approximately three to four times the interval of roller phase position for power reverse. Thus the contact elements 60-61 are maintained in circuit make position for a longer time than for the period of circuit make position of reverse current contact elements 66-62.

It is also to be noted that the system operation thus far described takes place only during the periods of gun firing action and while it is possible for the ammunition belt to move forward in the chute without stoppage. When, however, an obstruction develops the forward progress of the belt between the booster unit and gun feed chamber is brought to a standstill and the booster motor, if not stopped, is slowed down considerably. This slowing down result permits the roller 65 a proportionately longer period of time or "dwell" in the depressed phase and thus increases the plugging effect on the motor. The final result is that the motor will simply oscillate or rock back and forth without actually feeding the ammunition. As long as the trigger switch 29 is depressed the motor oscillation or rocking will continue and the ammunition belt will be jerked back and forth with no actual forward progress. It should be obvious by how that any obstruction which may occur either in the chute structure between the booster device and the gun feed chamber or in the gun itself will slow down the booster motor and cause the switch 40 to alter the power on-power reverse cycles sufficiently to prevent any further forward progress of the belt.

When the above described control system is applied to a turret gun installation 68 such as that generally indicated in connection with the aircraft 69 in Figure 9 it frequently happens that the gun ceases to function properly during violent or accelerated flight maneuvers. The cause of this is attributed to induced gravitational forces, usually referred to as "G" effects. After repeated tests it has been determined that for acceleration forces of approximately 3 G or less the first described control system will be adequate to maintain proper gun action. For values of approximately 3 G or greater the control system is rendered inoperative for continuing the flow of ammunition toward the gun. Therefore, a modified control of the type hereinafter to be described will introduce a control means competent to respond to and measure the G effects and adjust the electric circuit control switch 40 accordingly. Normally this means is maintained inoperative and switch 40 continues to rise and fall as noted, but when the acceleration forces reach or exceed substantially 3 G's the switch control means operates to hold the switch arm 56 in the power on or crest position (Figure 4) and the booster motor is free to feed ammunition continuously. By so doing, the full power of the booster motor

is available to force the rounds of ammunition through the chute at the time when the rubbing friction therebetween tends to retard or hamper the movement of ammunition toward the gun.

With reference to Figures 6, 7 and 8, the snap switch 40 is provided with a small U-shaped bracket 75 secured to the switch block by means of bolts 64 to provide a fixed mount for the switch controller member 78, the controller member being pivotally carried on this bracket by means of pivot pins 79 loosely carried in the bracket and peened into the side walls of the member 78 as clearly shown in Figure 8. The assembly may be mounted in any convenient manner to a fixed structure as the bracket 53. The member 78, which is freely pivotally carried on the bracket 75, is formed into a channel configuration and is further provided with spaced and longitudinally extending arms 81 as an integral and continuous part of the side walls. Each of the arms 81 is bent inwardly an amount sufficient to bring the inturned finger portion 82 under the switch arm 56 when observed in plan view (Figure 7). Thus when the member 78 pivots counterclockwise about the pins 79 (Figure 6) the finger elements 82 (dotted line position) contact the arm 56 at either side and interfere with the normal oscillating motion thereof under the influence of the rounds of ammunition.

Gravitational influence on member 78 is developed by an adjustable mass 83 mounted at the lower end of this member and secured thereto by means of a bolt 84 which is positioned in a longitudinal slot 85 and held in adjusted position by the nut 86. The slot 85 is formed in the base plate 81 of the channel member as shown in Figure 7. The mass 83 consists of a cup member 88 filled with lead or other material 89 which will permit high weight concentration in the relatively small space provided. Lead is preferred because of its unit weight and because it is easily handled. Further, the lead may be poured into the cup when molten so as to fill the slot in the bolt head and act as the means to prevent bolt rotation when making positional adjustments of the mass 83.

The means for retaining the member 78 in the inoperative (full line) position as shown in Figure 6 and to oppose the action of the mass 83 under the effects of gravitational forces comprises a resilient member or coil spring 90 which at one end is soldered or otherwise secured to a small plate 91, the latter element being retained in position under the head of bolt 64 (Figure 7). The opposite end of this spring 90 is adapted to fit loosely over the upset head of a retaining rivet 92 positioned in the base plate 83 of the channel member 78. Other spring retainer means such as a cup or recess formed in plate 83 may be provided for this same purpose.

The above described switch control members and its several parts and elements is easily fabricated and can be made as substantial and rugged as the conditions require. Some saving in weight can be effected by cutting away a portion of the channel base between the sections 87 and 93, the resulting aperture 94 will then provide the necessary access to the terminals of the switch block for the electrical wires (not shown) running between this switch and the remainder of the electrical system.

The control member 78 is adapted to respond to induced gravitational forces and in so doing the action thereof is transmitted to the oscillating switch arm 56 through the inturned finger

elements 82 to move the roller 65 out of the line of travel of the rounds of ammunition. As before noted when this control mechanism is applied to aircraft gun installations (Figure 9) the initial setting for the mass 83 and the strength of spring 90 should be arranged to maintain the member 78 in its inoperative position for gravitational forces of values up to substantially 3 G and to permit the member to pivot into switch interrupting position for forces of 3 G and greater. In one test installation it was found that faulty gun firing action developed when the gravitational force was about 3 G. Not all installations will be so affected that a setting of the mass 83 may be made for 3 G effects alone without regard to other factors. A few tests will soon indicate at what G value or range of G values faulty gun action develops and an adjustment can be made accordingly. Each new installation, however, must be considered separately so that the full sensitivity and action of the device can be realized. The position of the switch 63 relative to the path of travel of the ammunition belt, the direction and magnitude of calculated or expected gravitational influences and certain other factors shall all be directly determinative of the desired location and arrangement hereof and of the spring constant and mass values and settings to be made.

Obviously other system arrangements may be made or will suggest themselves after a study of the control system above described and certain structural modifications and changes will come to mind, but it is the aim hereof to cover all such variations as come within the scope of the claims appearing below.

What is claimed is:

1. A system for controlling the movement of an ammunition belt toward a machine gun having recoil operated means for initiating the advance of the belt in accordance with its firing cycle, said system comprising a reversible electric motor, a source of electrical current and a circuit including said motor, means driven by said motor for moving the ammunition belt toward said machine gun, means disposed in said electrical circuit and responsive to the movement of said ammunition belt for conditioning the motor for forward and reverse impulses in cycles synchronized substantially with the operating cycle of said recoil operated means, and a gun trigger in said electrical circuit for completing the circuit between said motor and current source upon initiation of gun firing.

2. A system for regulating the feed movement of belted cartridges toward a machine gun having recoil operated means adapted to establish a cyclic advance of the cartridges, and a cartridge magazine remote from the machine gun, said system comprising power operated means for feeding or retarding the belted cartridges in their movement from said magazine, and regulating means for cycling the power operated means to feed or retard the belted cartridges in accordance with the machine gun recoil cycle, said regulating means including an element arranged to have contact with the belted cartridges as the same move toward the machine gun and oscillate between a crest and a depressed position whereby said regulating means is rendered effective to cycle said power operated means.

3. A system for regulating the feed movement of belted cartridges toward a machine gun having recoil operated means adapted to establish a cyclic advance of the cartridges, and a cartridge

magazine remote from the machine gun, said system comprising power operated means of electrically reversible type for feeding or retarding the belted cartridges in their movement from said magazine, a source of electrical power for said power operated means, and regulating means for reversing the power for the power operated means to feed and retard the belted cartridges in cycles in accordance with the machine gun recoil cycle, 5 10 15 20 25 30 35 40 45 50 55 60 65 70 75

10 said regulating means including an element arranged to have contact with the belted cartridges as the same move toward the machine gun and oscillate between a crest and a depressed position whereby said regulating means is rendered effective to cycle said power operated means.

4. A system for feeding belted ammunition into an automatic gun which may be mounted on a highly maneuverable body such as an aircraft or the like the gun having means for advancing the belted ammunition thereinto in accordance with its firing cycle, comprising motor operated means for moving the belted ammunition toward the gun, control means normally operable intermittently for interrupting such operation of said motor operated means substantially in synchronization with movement of the ammunition by said advancing means, and means sensitive and movable in response to high acceleration of the entire system connected to said control means to override same upon movement of the acceleration responsive means, to energize said motor operated means for continuous operation in an ammunition advancing direction.

5. A system for feeding a cartridge belt into an automatic gun of highly mobile type having means actuated by the automatic gun for moving the cartridge belt into the same in accordance with its firing cycle, comprising a reversible electric motor, means driven by said motor and engageable with the cartridge belt for moving the same, a motor reversing switch for determining the direction of rotation of said reversible motor including an operating element extending into the path of movement of the cartridges such that successive cartridges will engage and cause said element to rise and fall, the rise and fall of said element being effective to operate said reversing switch to forward and reversing positions respectively in substantial synchronism with the operating cycle of said gun actuated means for moving the cartridge belt, and means responsive to a predetermined gravitational influence as a result of accelerated movement of the mobile automatic gun for moving said operating element to its raised position whereby said electric motor is conditioned for continuous forward rotation.

6. A system for feeding a belt of cartridges into an automatic gun which has means operated thereby for moving the cartridges thereinto as required by the gun firing cycle, said system comprising: reversible motor driven means for applying to the belt alternating forward impulses to move the belt toward the gun and reverse impulses, with the forward impulses of greater intensity than the reverse impulses, and means for controlling the application of said impulses to the belt in timed relation to the movement of cartridges past said motor driven means.

7. A system for feeding a belt of cartridges into an automatic gun, said system comprising reversible drive means for applying to the belt alternating forward impulses to move the belt toward the gun and reverse impulses, and means for controlling the application of said impulses to the belt in timed relation to the movement of

cartridges past said drive means and with the forward impulses of greater magnitude than the reverse impulses.

8. A system for feeding a belt of cartridges into an automatic gun, said system comprising reversible drive means for applying to the belt alternating forward impulses to move the belt toward the gun and reverse impulses, with the forward impulses of greater intensity than the reverse impulses, and means for controlling the application of said impulses to the belt in timed relation to the movement of cartridges past said drive means and with the forward impulses of longer duration than the reverse impulses.

9. A system for feeding a train of cartridges into an automatic gun that is provided with means for receiving cartridges in timed relation to the gun firing cycle, said system comprising: reversible drive means for applying to said train alternating forward impulses to move the train toward the gun and reverse impulses, and means for controlling the application of said impulses to the train with the forward impulses of greater magnitude than the reverse impulses and in timed relation to the movement of cartridges past said motor drive means to move the train toward the gun in accordance with said firing cycle.

10. In a system for feeding a train of cartridges into an automatic gun, reversible drive means for applying to said train alternating forward impulses to move the train toward the gun and reverse impulses, a member for following the cartridges for movement thereby in timed relation to the passage of individual cartridges past the drive means, and means operated by said member for controlling the application of said impulses to the train with the forward impulses of greater magnitude than the reverse impulses.

11. In a system for feeding a belt of cartridges into an automatic gun as required by the gun firing cycle, drive means for the belt including a reversible motor for applying to the belt alternating forward impulses to move the belt toward the gun and reverse impulses, means for causing the reverse impulses to be of less intensity than the forward impulses, and a reversing switch associated with the motor for controlling the application of said impulses to the belt in timed relation to the movement of cartridges past said drive means.

12. In a system for feeding a belt of cartridges into an automatic gun as required by the gun firing cycle, drive means for the belt including a reversible motor for applying to the belt alternating forward impulses to move the belt toward the gun and reverse impulses, means for causing the reverse impulses to be of less intensity than the forward impulses, a member for following the cartridges for movement thereby in timed relation to the passage of individual cartridges past the drive means, and a reversing switch operated by said member for controlling the application of said impulses to the belt.

13. In a system for feeding a belt of cartridges into an automatic gun as required by the gun firing cycle, drive means for the belt including a reversible motor for applying to the belt alternating forward impulses to move the belt toward the gun and reverse impulses, means for causing the reverse impulses to be of less intensity than the forward impulses, a member for fol-

lowing the cartridges for movement thereby in timed relation to the passage of individual cartridges past the drive means, a reversing switch operated by said member for controlling the motor, and snap action means connecting said member to the switch for holding the latter in forward or reverse positions.

14. In a system for feeding a belt of cartridges into an automatic gun as required by the gun firing cycle, drive means for the belt including a reversible motor for applying to the belt alternating forward impulses to move the belt toward the gun and reverse impulses, means for causing the reverse impulses to be of less intensity than the forward impulses, a member for following the cartridges for movement thereby in timed relation to the passage of individual cartridges past the drive means, a reversing switch operated by said member for controlling the motor, and snap action means connecting said member to the switch for holding the latter in forward or reverse positions, said snap action means being arranged to hold the switch in forward position during a greater portion of belt travel than in reverse position thereof.

15. In a system for feeding a belt of cartridges into an automatic gun, reversible drive means for applying to the belt alternating forward impulses to move the belt toward the gun and reverse impulses, means for controlling the application of said alternating impulses to the belt in timed relation to the movement of cartridges past said drive means and with the forward impulses of greater magnitude than the reverse impulses, and means responsive to acceleration of the system of predetermined degree for causing the drive means to apply a continuous forward driving force to the belt.

16. In a system for feeding a belt of cartridges into an automatic gun mounted upon a mobile support, reversible drive means for applying alternating forward impulses to move the belt toward the gun and reverse impulses, means for controlling the drive means to effect the alternate application of forward and reverse impulses to the belt with the forward impulses of greater magnitude than the reverse impulses, and means responsive to acceleration of the said support of predetermined degree to cause the drive means to apply a continuous forward driving force to the belt.

EDWARD J. MEYER.
